(57) CLAIM

The ornamental design for a garment, as shown and described.

DESCRIPTION

FIG. 1 is a perspective view of a garment, showing my new design;

FIG. 2 is a front elevational view thereof;

FIG. 3 is a front elevational view thereof;

FIG. 4 is a rear elevational view thereof;

FIG. 5 is a side elevational view thereof;

FIG. 6 is a side elevational view thereof;

FIG. 7 is a front elevational view thereof showing one leg opening worn high thigh;

FIG. 8 is a perspective view thereof showing two leg openings worn high thigh;

FIG. 9 is a front elevational view thereof;

FIG. 10 is a rear elevational view thereof;

FIG. 11 is a side elevational view thereof;

FIG. 12 is a side elevational view thereof;

FIG. 13 is a front elevational view of a garment, showing a second embodiment of my new design with one leg opening worn high thigh;

FIG. 14 is a perspective view showing two leg openings worn thigh high;

FIG. 15 is a front elevational view thereof;

FIG. 16 is a rear elevational view thereof;

FIG. 17 is a side elevational view thereof; and,

FIG. 18 is a side elevational view thereof.

The broken lines illustrating a human figure represent environment and form no part of the claimed design.

1 Claim, 10 Drawing Sheets
